PIANO PEDAL OPERATING ATTACHMENT

Elmer Grant Ege, Kansas City, Mo., and Fonville Winans, Baton Rouge, La., assignors to Jenkins Music Company, Kansas City, Mo., a corporation of Missouri

Application June 12, 1939, Serial No. 278,622

5 Claims. (Cl. 84—232)

Our invention relates to a piano pedal operating attachment and more particularly to a device which may be attached or used in connection with pianos enabling the operation of its pedals by children and persons with short legs.

The distance between the piano keyboard and the pedals is usually fixed by the construction of the instrument and is designed for average persons. Children and persons with short legs have difficulty in reaching the pedals. If the seat is low enough to enable them to reach the pedals, their hands are thrown into the wrong position for playing. If the hands and arms are in the proper position for playing, then difficulty is encountered by children and persons with short legs in operating the pedals.

If people with short legs such as children attempt to operate the pedals, which they cannot comfortably reach, it results in fatigue, impeding their progress in the study of the piano. Many pedal extensions have been suggested, but the difficulty and drawback of these has been that there has been no place provided to rest the heel of the foot.

One object of our invention is to provide an attachment which may be used with pianos enabling children and people with short legs to operate the pedals comfortably.

Another object of our invention is to provide a pedal operating means which may be readily adjusted in height and which will provide a foot rest for the feet of the player.

Other and further objects of our invention will appear from the following description.

In the accompanying drawing which forms part of the instant specification and is to be read in conjunction therewith and in which like reference numerals are used to indicate like parts in the various views;

Figure 1 is a side elevation of a pedal operating attachment for pianos, showing one embodiment of our invention.

Figure 2 is a top plan view of the pedal operating attachment shown in Figure 1.

Figure 3 is a rear elevation of the device shown in Figure 1.

Figure 4 is a sectional view taken along the line 4—4 of Figure 2.

Referring now to the drawing, we provide a pair of base members 1 and 2 to which we pivot U-rods 3 and 4. The rod 3 is pivoted in brackets 5, attached to member 1, and 6 attached to member 2. The rod 4 is pivoted in bracket 7 attached to member 1, and bracket 8 attached to member

2. The vertical portions of the rods 3 and 4 are of equal length and pivotally support a platform 9. The platform 9 is provided with a pair of brackets 10 at its rear end for pivotally receiving a transverse portion of the U-rod 3 and a pair of brackets 11 intermediate its rear and forward portions for pivotally receiving the ends 12 of the U-rod 4. The distance between brackets 6 and 8 is equal to the distance between brackets 10 and 11. It will be seen therefore, that we have provided a parallel motion and that the platform 9 will move to a plurality of positions, all of which are parallel to the base members 1 and 2. To the transverse portion 13 of the U-rod 4 we attach a clamp 14, adapted to receive an extension rod 15. When the thumb screw 16 of the clamp 14 is tightened, it will clamp rod 15 to the cross member 13. The end of rod 15 is provided with an upstanding portion 16', covered with a rubber or felt sleeve 17. The extension rod 15 is adapted to pass underneath the body of a piano and engage its rear end, as can readily be seen by reference to Figure 1. The position at which the clamp 14 secures the rod 15 to the cross rod 13 will determine the height at which the platform 9 will ultimately come to rest. It will be observed, by reference to Figure 1, that the front edge of the platform 19 is covered with felt 18. The parts are placed in the position shown in Figure 1, with the platform resting against the front edge of the piano. If it is desired to lower the platform, the thumb screw 16 of the clamp 14 is loosened and the base members 1 and 2 moved away from the piano allowing the platform 9 to pivot, lowering the position of the platform. When the desired height is reached, the thumb screw 16 is tightened. The assembly is then adjusted for proper height. For purposes of simplicity, we have shown only one pedal operating device. It will be observed, by reference to Figure 2 that we provide a slot 19 adjacent the forward end of the platform 9. Housed within the slot 19 we provide a ferrule 20 having a collar 21. The ferrule is externally threaded and adapted to receive a nut 22. A washer 23 of larger diameter than the width of the slot 19 is adapted to be clamped by the nut 22 against the under side of the platform 9. A rod 24 is slidable within the ferrule 21. A sleeve 25 is slidably mounted on the rod 24 and adapted to be secured thereto by a screw 26. The sleeve 25 carries a pedal 27. The pedal 27 is provided with a downwardly extending portion 28, adapted to enter the slot 19. The lower end of the rod 50

24 carries a rubber tip 29 adapted to rest upon the pedal 30 of the piano. The whole assembly may be positioned laterally until the slot is in line with the pedal 30. The ferrule 21 may be 5 adjusted longitudinally of the slot to bring the lower end of the rod over the pedal 30, which is to be operated. The feet of the operator rest upon the platform 9. The toe of the operator's foot may operate the pedal 30 through the extension pedal 27.

10 It is believed that the operation of our assembly will be clear from the foregoing description. It will be seen that we have accomplished the objects of our invention. We have provided a pedal 15 operating attachment for pianos which will enable the operation of the pedals of the piano by children and persons with short legs in a comfortable manner, eliminating the fatigue that would ensue if children attempt to operate the 20 pedals of a piano. The operation of the pedal is an important part in playing the piano and, in certain compositions, proper expression cannot be given without operating the pedals. It will be obvious, of course, that a plurality of rods 24 may 25 be fitted in the platform 9 to operate other pedals of the piano.

It will be understood that certain features and 30 sub-combinations are of utility and may be employed without reference to other features and sub-combinations. This is contemplated by and is within the scope of our claims. It is further 35 obvious that various changes may be made in details within the scope of our claims without departing from the spirit of our invention. It is, therefore, to be understood that our invention is not to be limited to the specific details shown and described.

Having thus described our invention, we claim:

1. A piano pedal operating attachment adapted 40 to be used with pianos including in combination a base member, an elongated tension member, means for securing one end of said tension member to the piano, means for securing the other end of said tension member to said base member, 45 a platform, supporting means pivotally secured to said base member, said supporting means carrying said platform in abutment with the piano, a rod slidably carried by said platform, the lower end of said rod being adapted to be supported by 50 the piano pedal to be operated, and an extension pedal carried by said rod above said platform.

2. A piano pedal operating attachment including in combination a base member, a rod, means for adjustably securing one end of said rod to said base member, said rod being formed with means adapted to abut the rear side of said piano whereby to position said base member a predetermined distance from the piano, a parallel motion supporting means pivotally secured to said base member, a platform supported by said supporting means for motion parallel to said base member, 10 said platform being adapted to abut the front side of a piano, a slot formed in said platform, a ferrule adjustably mounted in said slot, a vertical rod slidably mounted in said ferrule, and an extension pedal adjustably mounted upon said rod 15 above said platform.

3. In a piano pedal operating attachment, a base member, means for positioning said base member a predetermined distance from the piano, a parallel motion supporting means carried by 20 said base member, a platform supported by said means for movement parallel to said base member, said platform being adapted to abut the front side of the piano, a vertical rod slidably supported in said platform and an extension pedal 25 adjustably mounted upon said rod above said platform.

4. A pedal operating attachment for pianos including in combination a platform, means for mounting said platform above the pedals of a 30 piano, a vertical rod slidably carried by said platform, means carried by the lower end of said rod adapted to rest upon the pedal to be operated, an extension pedal slidably mounted upon said rod 35 above said platform and means for adjustably securing said extension pedal to said rod.

5. In a pedal operating device for pianos, a platform, means for adjustably positioning said platform a predetermined distance above a piano pedal to be operated, said platform being formed 40 with a slot, a ferrule adjustably mounted in said slot, a vertical rod slidably positioned in said ferrule, the lower end of said rod being provided with means adapted to contact the pedal to be operated, an extension pedal adjustably secured to 45 said rod above said platform, said pedal being formed with a downwardly extending portion adapted to extend into said slot whereby to prevent rotation of said extension pedal.
